UNITED STATES PATENT OFFICE.

HENRY T. C. HEUCK, OF CHAMPAIGN, ILLINOIS.

WATER-CLOSET VALVE.

SPECIFICATION forming part of Letters Patent No. 655,233, dated August 7, 1900.

Application filed March 14, 1900. Serial No. 8,624. (No model.)

To all whom it may concern:

Be it known that I, HENRY T. C. HEUCK, a citizen of the United States, and a resident of Champaign, Champaign county, State of Illinois, have invented certain new and useful Improvements in Water-Closet Valves; and my preferred manner of carrying out the invention is set forth in the following full, clear, and exact description, terminating with 10 claims particularly specifying the novelty.

This invention relates to all water-tanks, and more especially to that class of devices used therein which are known as "water-tank valves;" and the object of the same is 15 to produce a valve of this kind so constructed as to be conveniently interchangeable to adapt it to close either with or against the pressure of the inflowing water and without the necessity of disarranging the parts.

20 To this end the invention consists in the details of construction hereinafter described and claimed and as illustrated in the accompanying drawings, wherein—

Figure 1 is a sectional view of this device 25 in one arrangement, the valve being open. Fig. 2 is a similar view of this device in another arrangement, the valve being closed and a slightly-different form of fulcrum being therein illustrated, although it will be 30 clear that this fulcrum could be used in Fig. 1.

Referring to the drawings, T is the bottom 35 of the tank, through which extends the body B of the valve, with washers W above and below and a nut N for preventing leakage. C is the coupling connecting the lower end of the body with the service-pipe outside the tank and inside the latter. I is the inlet, and F the float, mounted on a rod R, all of which parts may be of the ordinary or any 40 well-known construction.

Coming now more particularly to the present invention, the letter v designates a valve, which is by preference of rubber or other soft material, globular in shape, and held between nuts n on the valve-rod r, and u is an upper valve-seat at the lower end of the body B, while l is a lower valve-seat formed within the coupling C. It may here be remarked 45 that the coupling is of such length that the valve v stands midway between these seats when the tank is empty and the float is down, and it approaches its proper seat as the tank

fills and the float rises. The rod r passes upward through the bore of the body B, whose upper end may carry a stuffing-box s, and 55 the rod is pivoted to the float-rod R, as described below. On the body is cast or formed an ear e opposite the inlet I and both ear and inlet are tapped with holes adapted to receive a plug p. In Fig. 1 the fulcrum f is 60 a rod screwed at its lower end into the hole not occupied by the plug and rising rigidly therefrom. In Fig. 2 the same arrangement prevails, except that the fulcrum-rod is in two members pivotally connected, as at c, and the 65 lower member screws into the hole. The only difference is that the former arrangement requires a little looseness of pivots, described below, which may be produced by elongating one of them, as shown in dotted 70 lines, whereas in the latter arrangement the pivot avoids the necessity for this looseness, which arises from the fact that the two pivots approach each other when the float-rod is moved from a horizontal position. In both 75 figures of the drawings, x is the fulcrum-pivot connecting the float-rod R with the fulcrum-rod f, and y is the weight-pivot connecting the float-rod R with the valve-rod r. In both figures also the parts are preferably so proportioned that the valve v stands midway between the seats u and l when the float F is down, although it will be clear that by using a coupling C of different length or adjusting the valve on the rod r or in any way bringing either of the seats into different relative 80 position with respect to the valve a different static condition of the device would be produced. The whole is furnished to the plumber in the shape shown in the drawings 85 except that either form of fulcrum may be sold him, as preferred, and he is at liberty to put the device into the consumer's tank with the fulcrum at either side of the body, because it can afterward be quickly altered, if 90 desired. The arrangement shown in Fig. 1 is adapted for the closing of the valve with and assisted by the rush of the inflowing water, for the latter will push upward slightly on the valve v and will assist the float, which 95 in rising draws upward on the rod r until the valve is closed against the seat u. The arrangement shown in Fig. 2 is adapted to close the valve against the inflowing water,

because as the float rises the rod R turns over the intermediate fulcrum x and pushes the valve v downward until it closes against the seat l . The transposition from one arrangement to the other is quickly and easily accomplished by disconnecting the rod R at the points x and y , transposing the fulcrum rod and plug, and reconnecting the pivots x and y , so that the fulcrum-pivot shall be intermediate instead of the weight-pivot, or vice versa.

It will be clear from this description that it is entirely immaterial whether the fulcrum has a pivot within its body or one of the pivots to the float-rod is loose, and, in fact, any other well-known means might be employed for permitting lateral variation between the points x and y as the float rises and falls. Other changes in the details of construction may also be made without departing from the spirit of my invention, and the exact sizes, shapes, materials, and proportions of parts are susceptible of considerable latitude.

What is claimed as new is—

- 25 1. In a water-tank valve, the combination with the body passing through the bottom of the tank and having a valve-seat at its lower end, means for making a water-tight connection between the body and tank, a coupling below the latter connecting the body with the service-pipe, and a valve-seat within the coupling; of a valve adapted to close against either seat, a float and float-rod, pivotal connections between the latter and the valve, a fulcrum-pivot for the rod, and means for supporting said pivot at either side of said connections as desired, substantially as set forth.
- 30 2. In a water-tank valve, the combination with the body passing through the bottom of the tank and having a valve-seat at its lower end, means for making a water-tight connection between the body and tank, a coupling below the latter connecting the body with the service-pipe, and a valve-seat within the coupling; of a valve adapted to close against either seat, a float and float-rod, pivotal connections between the latter and the valve, a fulcrum-

- 40 45

pivot for the rod, an ear on said body opposite the inlet-pipe, threaded sockets in the ear and pipe, and a plug and fulcrum-rod interchangeably seated in these sockets with the rod supporting the fulcrum-pivot, substantially as set forth.

3. In a water-tank valve, the combination with the body passing through the bottom of the tank and having a valve-seat at its lower end, means for making a water-tight connection between the body and tank, a coupling below the latter connecting the body with the service-pipe, and a valve-seat within the coupling; of a valve adapted to close against either seat, a float and float-rod, pivotal connections between the latter and the valve, a fulcrum-pivot for the rod, an ear on said body opposite the inlet-pipe, sockets in the ear and pipe, and a plug and fulcrum-rod interchangeably seated in said sockets, the fulcrum-rod being in two members pivotally connected with each other and the uppermost supporting the fulcrum-pivot, all as and for the purpose set forth.

4. In a water-tank valve, the combination with the body passing through the bottom of the tank and having two opposing valve-seats near its lower end, and means for making a water-tight connection between the body and tank; of a valve adapted to close against either seat, a float and float-rod, pivotal connections between the latter and the valve, a fulcrum-pivot for the rod, sockets on said body at opposite sides thereof, and a plug and fulcrum-rod interchangeably seated in said sockets, the fulcrum-rod being in two members pivotally connected with each other and the uppermost supporting the fulcrum-pivot, all as and for the purpose set forth.

In testimony whereof I have hereunto subscribed my signature this the 12th day of March, A. D. 1900.

HENRY T. C. HEUCK.
